United States Patent Office

Des. 215,628

Patented Oct. 14, 1969

215,628

DISPLAY STAND FOR DISHES AND THE LIKE

Eirvan C. Cantrell, 1801 W. Anaheim St.,
Long Beach, Calif. 90813

Filed Oct. 31, 1968, Ser. No. 14,244

Term of patent 14 years

Int. Cl. D6—01

U.S. Cl. D80—9

FIG.1

I claim:

The ornamental design for a display stand for dishes and the like, as shown.
